CLAIM

The ornamental design for a buckle assembly, as shown and described.

DESCRIPTION

FIG. 1 is a front perspective view of a first embodiment of a buckle assembly having a base and a latch.

FIG. 2 is a rear perspective view of the buckle assembly of FIG. 1.

FIG. 3 is a front view of the buckle assembly of FIG. 1.

FIG. 4 is a rear view of the buckle assembly of FIG. 1.

FIG. 5 is a left side view of the buckle assembly of FIG. 1.

FIG. 6 is a right side view of the buckle assembly of FIG. 1.

FIG. 7 is a top view of the buckle assembly of FIG. 1.

FIG. 8 is a bottom view of the buckle assembly of FIG. 1.

FIG. 9 is a front perspective view of the base of the buckle assembly of FIGS. 1-8 shown in isolation for ease of illustration.

FIG. 10 is a rear perspective view of the base of FIG. 9.

FIG. 11 a front view of the base of FIG. 9.

FIG. 12 is a rear view of the base of FIG. 9.

FIG. 13 is a left side view of the base of FIG. 9.

FIG. 14 is a right side view of the base of FIG. 9.

FIG. 15 is a top view of the base of FIG. 9.

FIG. 16 is a bottom view of the base of FIG. 9.

FIG. 17 is a front perspective view of the latch of the buckle assembly of FIGS. 1-8 shown in isolation for ease of illustration.

FIG. 18 is a rear perspective view of the latch of FIG. 17.

FIG. 19 is a front view of the latch of FIG. 17.

FIG. 20 is a rear view of the latch of FIG. 17.

FIG. 21 is a left side view of the latch of FIG. 17.

FIG. 22 is a right side view of the latch of FIG. 17.

FIG. 23 is a top view of the latch of FIG. 17.

FIG. 24 is a bottom view of the latch of FIG. 17.

FIG. 25 is a perspective view of the buckle assembly of FIGS. 1-8, illustrating environmental matter in broken lines.

FIG. 26 is a front perspective view of a second embodiment of the buckle assembly having a base and a latch.

FIG. 27 is a rear perspective view of the buckle assembly of FIG. 26.

FIG. 28 is a front view of the buckle assembly of FIG. 26.

FIG. 29 is a rear view of the buckle assembly of FIG. 26.

FIG. 30 is a left side view of the buckle assembly of FIG. 26.

FIG. 31 is a right side view of the buckle assembly of FIG. 26.

FIG. 32 is a top view of the buckle assembly of FIG. 26.

FIG. 33 is a bottom view of the buckle assembly of FIG. 26.

FIG. 34 is a front perspective view of the base of the buckle assembly of FIGS. 26-33 shown in isolation for ease of illustration.

FIG. 35 is a rear perspective view of the base of FIG. 34.

FIG. 36 a front view of the base of FIG. 34.

FIG. 37 is a rear view of the base of FIG. 34.

FIG. 38 is a left side view of the base of FIG. 34.

FIG. 39 is a right side view of the base of FIG. 34.

FIG. 40 is a top view of the base of FIG. 34.

FIG. 41 is a bottom view of the base of FIG. 34.

FIG. 42 is a front perspective view of the latch of the buckle assembly of FIGS. 26-33 shown in isolation for ease of illustration.

FIG. 43 is a rear perspective view of the latch of FIG. 42.

FIG. 44 is a front view of the latch of FIG. 42.

FIG. 45 is a rear view of the latch of FIG. 42.

FIG. 46 is a left side view of the latch of FIG. 42.

FIG. 47 is a right side view of the latch of FIG. 42.

FIG. 48 is a top view of the latch of FIG. 42.

FIG. 49 is a bottom view of the latch of FIG. 42; and,

FIG. 50 is a perspective view of the buckle assembly of FIGS. 26-33, illustrating environmental matter in broken lines.

The broken lines depict portions of the buckle assembly that form no part of the claimed design. The broken lines immediately adjacent to the shaded areas define the bounds of the claimed design and form no part thereof. The broken line showing of a partial helmet and straps in FIGS. 25 and 50 is for the purpose of illustrating environmental structure and forms no part of the claimed design.
